UNITED STATES PATENT OFFICE

JOHN A. ANDERSON, OF GRAND RAPIDS, MICHIGAN

CURTAIN STRETCHER

Application filed May 26, 1930. Serial No. 455,495.

The present invention relates to curtain stretchers, and more particularly to such devices used for stretching curtains after laundering and during the drying thereof.

5 The principal object of the invention is to provide such a device which is capable of maintaining a uniform tension on all parts of a curtain in such a manner that the edges thereof remain straight. A further object of 10 the invention is to provide a curtain stretcher which is compact and which, when not in use, occupies a minimum amount of space; and still further to provide such a device which may be quickly and easily applied to 15 or removed from a curtain.

These and any other objects, hereinafter appearing are attained by, and the invention finds preferable embodiment in, the structure or device hereinafter particularly described 20 in the body of this specification and illustrated by the accompanying drawing, in which:

Figure 1 is a front elevational view of the device applied to a curtain, portions of the latter being broken away;

Figure 2 is a sectional view taken on line 2—2 of Figure 1;

Figure 3 is a sectional view taken on line 3—3 of Figure 1; and

30 Figure 4 is a sectional view taken on line 4—4 of Figure 1.

The device shown in this drawing comprises four principal members, each adapted to retain one edge of a curtain, and a number of clamps so affixed to these members as to secure them in gripping relation to each other and to the curtain.

40 The upper bar 1 is a solid rod flattened for the purpose of better displaying the measuring indicia 2 thereon. This bar is adapted to slide through the hem 3 at the upper end of a curtain 4 and thus retain this upper edge of the curtain. This upper bar may be provided with hook-receiving apertures 5 near either end thereof, into which may be inserted the lower ends of the hooks 6, the upper ends of which may be hooked over the closeline 7 so that the device may be suspended therefrom during the drying of the curtain.

The lower bar 8 is an integral bar bent at 9 to form the front arm 10 and rear arm 11. The front arm of this bar is provided with a scale of measuring indicia 12 identical with the scale 2 on the upper bar. The inner 55 surface of the lower bar is provided with a relatively thin strip 13 of some rough semi-yielding material, preferably felt, which may be glued thereto. This bar 8 is secured to the lower edge of the curtain 4, with front 60 and rear arms on opposite sides thereof, by means of the clamping members 14, which may be of any suitable construction. These clamp members serve to urge the front and rear arms of the bar together, the felt strip 65 13 augmenting the frictional grip on the curtain. This bar 8 is preferably relatively heavy in order to insure a maximum amount of tension on the curtain while the stretching device is being applied thereto.

The vertical side member 15 is a flexible integral bar bent to form a bight portion 16 which is adapted to embrace the upper bar 1, and has front and rear arms 17 and 18 respectively. The inner surface of the member 15 is also lined with a felt strip 19 to provide a more effective gripping surface; and this member is clamped to an edge of the curtain, and to corresponding ends of the upper and lower bars by means of the 70 clamping members 20. The other vertical side member 21 is constructed and applied similarly. The side members 15 and 21 are provided with corresponding scales of measuring indicia 22 and 23 on the front surfaces 75 thereof.

The measuring indicia on the device enables the application of the invention to a curtain in such manner that the curtain will maintain its true proportions.

80 It will thus be seen that by the use of this device a curtain may be stretched uniformly, and with no danger of "scallops" appearing along the edges thereof such as are formed by the usual curtain stretchers having pins which engage the curtain.

In cases where the curtain to be stretched is narrow, the lower bar need not be provided with clamping members, as the front and rear arms of this bar would be sufficiently 85 90 95 100

urged together by the action of the side members and their clamps.

When the curtain to be stretched has both upper and lower hems, the lower bar may 5 function in the same manner as the upper bar, that is, by passing through the lower hem; and may even be replaced by a bar of identical construction with the upper bar. Conversely, if the material to be stretched 10 has neither upper or lower hem, the upper bar may be replaced by a bar of identical construction with the lower bar, and with or without clamping members.

The invention being intended to be pointed out in the claims, is not to be limited to or 15 by details of construction of the particular embodiment thereof illustrated by the drawing, or hereinbefore described.

I claim:

- 20 1. In a curtain stretcher, upper and lower bars adapted to retain respectively the upper and lower edges of a curtain, a pair of side members, each formed of a single piece of yieldable material and bent intermediate 25 its ends to form front and rear arms adapted to receive therebetween a side of said curtain and a bight intermediate said arms adapted to slidably receive the end portion of one of said bars, and clamping means for clamping 30 together said front and rear arms of the side members.
2. In a curtain stretcher, upper and lower bars adapted to retain respectively the upper and lower edges of a curtain and having 35 thereon corresponding measuring indicia, a pair of side members each formed of a single piece of material bent intermediate its ends each having front and rear arms adapted to receive therebetween a side of said curtain and having a bight intermediate said arms adapted to receive the end portion of one of said bars, the front surfaces of the arms of

the said side members being provided with corresponding measuring indicia, and clamping means for clamping together said front and rear arms with a side of said curtain therebetween and said bar therebetween in 40 said bight.

3. In a curtain stretcher, an upper bar adapted to be slid within the upper hem of a curtain, a lower bar having front and rear arms adapted to receive therebetween the 45 lower edge of said curtain, a pair of side members each formed of a single piece of yieldable material and bent intermediate its ends to form front and rear arms adapted to receive therebetween a side of said curtain 50 and also an end of each of said bars, semi-yielding material secured to the inner surfaces of the front and rear arms of the side members, semi-yielding material secured to the inner faces of the front and rear arms of 55 said lower bar, and clamping means for clamping together front and rear arms of said side members with a side of said curtain and the end portions of said bars therebetween, and means for clamping together the 60 front and rear arms of said lower bar.

4. In a curtain stretcher, upper and lower bars adapted to retain respectively the upper and lower edges of a curtain, means for suspending the upper bar from a mooring, the 65 lower bar serving to stretch the curtain, a pair of side members each formed of a strip of material bent intermediate its ends to form front and rear arms adapted to receive therebetween a side of the stretched 70 curtain and also an end of each of said bars, and clamping means for clamping together 75 said front and rear arms.

In testimony whereof I have hereunto set my hand at Grand Rapids, Michigan, this 105 17th day of May, 1930.

JOHN A. ANDERSON.
